UNITED STATES PATENT OFFICE.

JOHN W. CADY, OF HAMILTON, RHODE ISLAND.

CHURN.

SPECIFICATION forming part of Letters Patent No. 323,784, dated August 4, 1885.

Application filed March 12, 1885. (No model.)

To all whom it may concern:

Be it known that I, JOHN W. CADY, of Hamilton, in the county of Washington and State of Rhode Island, have invented certain new and useful Improvements in Churns; and I do hereby declare that the following is a full, clear, and exact description thereof, reference being had to the accompanying drawings, and to the letters of reference marked ⁵ thereon, which form a part of this specification.

This invention relates to that class of churns that are suspended on pivots and subjected to a swinging pendulum motion, whereby the ¹⁵ dasher is moved up and down in the churn through the agency of levers attached to the supporting-frame.

Figure 1 shows an end elevation of the churn and the improvements. Fig. 2 is a top ²⁰ plan view of the same. Fig. 3 shows a side elevation of the whole apparatus. Fig. 4 is a side elevation with parts of the supporting-frames, and also of the swinging frame, removed to show the arrangement of the interior.

The churn and its working attachments are supported upon a frame, D, which consists of an oblong top frame standing on four legs. In the middle of each side of the top frame a ³⁰ bearing, a' , is placed, to receive the pivots on which the churn-frame F swings. This frame F is made with a broad bottom, that supports the churn, and two side pieces, which extend up on each side of the churn to the top, where they are fastened together by a cross-piece, J, that also serves as a guide for the dashers C C. A double bracket, or "walking-beam," as it may be called, B, is attached to the churn-frame F, which it incloses. It ³⁵ has pivots attached on each side at the middle, which pivots rest in the bearings a' and support the churn and swinging frame F. The dashers, of which there are two, C C, have the upper ends of their staves made to slide in openings in the cross-bar J, and also through like openings in a cross-bar, E, near the middle of the churn-frame. The staff of each dasher C C is made in two parts, joined together just above the top of the churn with ⁴⁰ a bolt or other fastening that can easily be removed to admit of the churn being taken

out of the frame. The churn may be kept in place in the frame F by means of a dowel, e' , made fast in the bottom of the frame, and entering a recess in the bottom of the churn, ⁵⁵ or by other suitable means. Two levers, A A, have their inner ends pivoted one to each dasher-staff C, and their outer ends supported by pivots G, held in studs on each end of the top frame. A long slot is made in the outer ⁶⁰ end of each lever A, through which the supporting-pivot passes, the object of the slots being to allow of a sliding motion in the levers. The two levers A A rest at about the middle of each on the outer ends of the walking-beam B, to which they are confined by the caps L L, attached to the under sides of the levers.

The operation is as follows: The churn j, with a proper quantity of cream, is placed ⁷⁰ in the frame F, as shown in Fig. 1. The lower parts of the dashers C C, being already in the churn, are secured to their upper parts, which remain in the frame. The operator, by means of the rod H, which has a hook in ⁷⁵ its end to catch into a staple in the side of the frame F, gives a swinging pendulum motion to the churn and frame F. As the frame F swings to one side, the arm of the walking-beam B on that side raises the middle of the ⁸⁰ lever A on that side, and as the outer end of the lever is held by the pivot in that end the inner end of the lever is thrown up, carrying with it the dasher that is attached to it. At the same time the other end of the walking-beam B is depressed, and by the downward ⁸⁵ motion of the lever A on that side the dasher attached is forced down. By successive swinging motions back and forward the two dashers are made to move up and down past each other in the churn with great effect. The easy swinging motion of the frames, the two dashers balancing each other, together with the momentum of frame and churn, with its contents, combine to produce a great effect ⁹⁰ with a comparatively small exertion of power by the operator. The motions of the dashers in the churn sliding past each other are very effective in churning the cream and in working the butter together in one mass after it ⁹⁵ has "come."

Having thus described my improvements,

what I claim as my invention, and desire to secure by Letters Patent, is—

The combination of the frame T, suspended on pivots on the frame D, with the walking-beam B, slotted levers A A, connected to said beam, and dashers C C, connected to said levers, substantially as herein described, and for the purpose set forth.

In witness whereof I hereunto set my hand.

JOHN W. CADY.
